UNITED STATES PATENT OFFICE.

AUGUST B. SCHLESINGER, OF DETROIT, MICHIGAN, ASSIGNOR TO AMERICAN CAR AND FOUNDRY MOTORS COMPANY, OF NEW YORK, N. Y., A CORPORATION OF DELAWARE.

AIR-COMPRESSOR UNIT.

Application filed February 18, 1927. Serial No. 169,194.

Reference is had to the accompanying drawings, which illustrate the preferred form of the invention, though it is to be understood that the invention is not limited to the exact 5 details of construction shown and described, as it is obvious that various modifications thereof within the scope of the claims will occur to persons skilled in the art.

In said drawings:

10 My invention relates to air compressors and more particularly to an air compressor assembly or unit for installation on an internal combustion engine.

15 The principal object of this invention is to provide an air compressor unit or assembly which when arranged in operative position on an internal combustion engine will be operatively connected therewith and driven thereby and provide an oil-tight connection between the engine casing and the compressor.

20 A further object of the invention resides in the provision of a compressor unit in combination with an internal combustion engine and so arranged that the engine casing will receive and house the compressor piston operating means and thereby dispense with the usual compressor crank case.

25 The invention also contemplates an air compressor unit having a drive or operating element which with the compressor attached to the engine casing mates with a rotary drive element of the internal combustion engine to be driven by the latter.

30 Another object of this invention is the provision of an air compressor for use with an internal combustion engine which is assembled in toto as a unit and then applied as a unit to the internal combustion engine; the unit consisting of cylinders and cooperating 35 pistons with the cylinders capable of adjustment relative to the crank shaft to which the pistons are connected, whereby to vary the clearance space between the top of the pistons and the cylinder heads when the pistons are 40 in their extreme upper position and thus vary to a predetermined degree the air compressed by said pistons.

In the drawings:

Fig. 1 is a vertical sectional view of my 50 air compressor unit associated with an internal combustion engine, the view being taken on the line 1—1 of Fig. 2, the casing of the engine being shown in broken lines;

Fig. 2 is a vertical sectional view taken on 55 the line 2—2 of Fig. 1.

Referring to the invention in detail, a conventional internal combustion engine casing is designated at 5 and is provided with an opening 6 at one end of its upper wall, the opening extending entirely across the casing and located above the engine drive shaft 7.

An air compressor unit or assembly is designated at 10 and comprises a plurality of cylinders 11 in which air compressing pistons 12 are mounted.

For the purpose of mounting the compressor unit or assembly on the engine casing 5 so as to take power from the drive shaft 7 to operate the compressor and at the same time close the opening 6, the pump cylinders 11 are cast with a continuous hollow base or flange 13 the lower edges of which are formed into relatively heavy horizontal supporting attaching portions 17 which rest upon the casing 5 and surround the opening 6. Spaced hollow bosses 14 are provided in the lower edge of the base or flange 13 to take attaching bolts 15 engaging registering openings 16 around the edges of the opening 6. By 70 adjusting the bolts 15 the casing 5 and base or flange 13 will be drawn tightly together producing a liquid and gas-tight fit.

Disposed below the base or flange 13 is a 75 crank shaft 19 operatively connected with the pistons 12 by means of connecting rods 20, and journaled in bearing brackets 18 which latter are secured by suitable means to the bearing portions 17, heretofore mentioned. A relatively large pinion 21 is fixed to one 80 end of the crank shaft 19 which meshes with a drive pinion 22 fixed to the drive shaft 7.

The device of the present invention is made and assembled for attachment as a unit to an internal combustion engine and clearance 85 spaces between the tops of the several pistons and the cylinders have been predetermined. It becomes necessary sometimes to vary the clearance space to obtain a different capacity of the unit to meet various conditions, and therefore it is desirable to so form the unit that the parts thereof may be adjusted whereby to regulate or control the degree or amount 90 of air compressed by the pistons. To that end the invention contemplates the use of shims 105 23 which are interposed between the under faces of the attaching portion 17 and the upper faces of the bearing brackets 18. This, it will be apparent, will adjust the cylinders 110 relative to the pistons, or vice versa, and thus

equally vary the clearance between each piston and cylinder when the former are in their uppermost position, to a degree corresponding to the shims employed; it being also 5 apparent that the desired clearance may be obtained to a nicety.

It will be apparent that by varying the number of shims interposed between the portion 17 and bearing 18, the casing 13 may be 10 adjusted relative to the crank shaft, thus varying the strokes of the pistons 12 relative to the cylinders 11 and consequently varying the compression produced by said pistons.

The entire unit may be adjusted relative 15 to the engine casing by interposing between or removing from between the portion 17 and the casing, shims or gaskets as long as the pinion 21 is retained in driving engagement with the pinion 22 thereby providing a means 20 for adjusting the unit to compensate for wear or to afford proper meshing of the pinion 21 and pinion 22 in the event of slight variations in mechanical construction which sometimes occur.

With my invention it will be apparent that 25 the compressor unit may be readily installed on the engine casing and incident to such installation the pinion 21 will be brought into operative relation to the pinion 22. It will be further noted that this combination obviates the necessity of the usual crank case for 30 the crank shaft 19.

What is claimed is:

1. In an air compressor, the combination of 35 cylinders, an attaching base, pistons, a crank shaft to which the pistons are connected, and bearings supporting the crank shaft and secured to the base, said base being adjustable with respect to the bearings whereby to simultaneously vary the clearance between the pistons and cylinders when the former are in 40 their uppermost position.

2. In an air compressor, the combination of cylinders, an attaching base, pistons, and a

crank shaft to which the pistons are connected, means for varying the clearance between the pistons and the cylinders whereby to vary the air compressed comprising bearings secured to the attaching base and supporting the crank shaft, said base being adjustable 50 with respect to the bearings.

3. In an air compressor, the combination of cylinders, pistons, an attaching base, a crank shaft to which the pistons are connected, bearings supporting said crank shaft and removably secured to the base, and means interposed between the bearings and base to vary the connection of the bearings therewith whereby to vary the clearance between the 55 pistons and cylinders.

4. An air compressor comprising in combination, a unit having a plurality of pistons, a crank shaft to which the pistons are connected, a plurality of connected cylinders in which the pistons work, and bearings secured to the cylinders for mounting the crank shaft, said bearings being connected to said cylinders in such a manner as to permit adjustment 60 of the cylinders with respect thereto to vary the clearance between each piston and its cylinder to an equal degree.

5. An air compressor for attachment to an internal combustion engine comprising in combination, a unit having a plurality of connected cylinders, a piston in each cylinder, a crank shaft to which said pistons are connected, a gear on the crank shaft rotatable by the engine to operate the pistons, and bearings supporting said crank shaft, said bearings being adjustably secured to the cylinders 65 whereby the position of the latter may be varied with respect to said bearings to vary the clearance between the pistons and cylinders.

In witness whereof I have hereunto set my 70 hand.

AUGUST B. SCHLESINGER.
